United States Patent Office

Des. 219,378
Patented Dec. 8, 1970

219,378

FLOOR COVERING OR SIMILAR ARTICLE

Joseph Robert Cecchine, Manville, N.J., assignor to
Johns-Manville Corporation, New York, N.Y., a cor-
poration of New York

Filed May 26, 1969, Ser. No. 17,322

Term of patent 14 years

Int. Cl. D25—01

U.S. Cl. D18—2

Fig. 2.

Fig. 3.

Fig. 4.

Fig. 5.

FIG. 1 is a top plan view of a full repeating unit of a floor covering or similar article showing my new design; and

FIGS. 2 through 6 are embodiments of the floor covering or similar article shown in FIG. 1.

The floor covering or similar article shown in the drawing is of typically conventional thickness.

I claim:

The ornamental design for a floor covering or similar article, substantially as shown and described.
